INSULATING SUPPORT FOR SIZZLE PLATTERS

James J. Melich and Edwin G. Melich, Chicago, Ill.

Application October 20, 1954, Serial No. 32,743

Term of patent 14 years

(Cl. D44—10)

FIG. 1

FIG. 2

FIG. 3

FIG. 4

Fig. 1 is a top plan view;

Fig. 2 is a bottom plan view;

Fig. 3 is a side elevational view partly in section showing the relation of the interior grooves and the exterior rim; and

Fig. 4 is an end elevational view.

We claim:

The ornamental design for an insulating support for sizzle platters, as shown and described.
